ROTARY HEAD ASSEMBLY FOR TAPE RECORDERS AND THE LIKE

Jack R. Goodrich, Newark, Calif., assignor to Ampex
Corporation, Redwood City, Calif., a corporation of
California

Filed Mar. 24, 1969, Ser. No. 16,417

Term of patent 14 years

Int. Cl. D14—01

U.S. Cl. D26—14

FIG. 1 is a front, top and right side perspective view of a rotary head assembly for tape recorders and the like showing my new design; and

FIG. 2 is a rear, top and left side perspective view of the unit of FIG. 1, the bottom being conventionally plain.

I claim:

The ornamental design for a rotary head assembly for tape recorders and the like, substantially as shown and described.
